(57) **CLAIM**

The ornamental design for a towel bar bracket, as shown and described.

DESCRIPTION

FIG. 1 is a top plan view of the towel bar bracket of my new design;

FIG. 2 is a front elevation view;

FIG. 3 is a bottom plan view;

FIG. 4 is a rear elevation view;

FIG. 5 is a perspective view;

FIG. 6 is a right side elevation view; and,

FIG. 7 is a left side elevation view.

The broken-line disclosure in the view is for illustrative purposes only, with the claimed design limited to the full-line disclosure.
